UNITED STATES PATENT OFFICE.

RICHARD SCHOLZ, OF LORAIN, OHIO, ASSIGNOR TO NATIONAL TUBE COMPANY, A CORPORATION OF NEW JERSEY.

COUPLING-GAUGING MACHINE.

Application filed April 5, 1928. Serial No. 267,660.

This invention relates to coupling gauging machines and, while not limited thereto, relates more particularly to double-ended gauging machines so constructed that one coupling may be threaded onto one end of the gauge-shaft while one is being removed from the other end thereof, whereby a single machine will serve two operators.

One object is to provide a novel form of control for the machine operable by a reciprocatory movement of the gauge-shaft which is under the control of the operator.

Another object is to provide a machine of this class having the novel combination, construction and design of parts, hereinafter described and illustrated in the accompanying drawings.

In the drawings—

Figure 1 is a side elevation of a gauging machine constructed in accordance with this invention.

Figure 2 is an end elevation thereof.

Figure 3 is an enlarged fragmentary detail view showing the construction of the gauging head.

Figure 4 is a similar view sectioned at the rear of the gauge-plug.

Referring more particularly to the drawings the numeral 2 designates the machine housing having a horizontal hollow gauge-shaft 3 journaled therein adjacent its upper end. The shaft 3 is free to slide longitudinally in its bearings for a purpose to be described.

A worm-wheel 4 is slidably keyed on the shaft 3 and is meshed with a worm 5 secured on a drive-shaft 6 journaled in the housing 2 below the shaft 3. The shaft 6 has one end projected beyond the housing, and a pulley 7 is secured on said projected end.

A motor 8 is mounted on the housing 2 and has its armature shaft provided with a pulley 9. A belt 10 is trained over the pulleys 7 and 9 so as to form a driving connection between the motor 8 and drive-shaft 6.

A bolt-rod 12 extends through the hollow gauge-shaft 3 and projects from each end thereof and is held against movement relative to the shaft by a set-screw 14. Threaded gauge-plugs 13 are mounted on the ends of the rod 12 and held in position by nuts 15.

A motor controller 16 is mounted in the housing 2, and has its operating plunger 17 connected to the end of one of the arms 18 of a bell-crank lever 19 which is pivotally

mounted on the housing 2. The other arm 20 of the bell-crank lever terminates in a clevis or fork 21 which fits into a groove 22 in the gauge-shaft, so that reciprocation or sliding movement of the gauge-shaft 3 will rock the lever 19 about its pivotal mounting and thereby cause the arm 18 to actuate the motor controller 16. The controller is of the ordinary type which normally remains in neutral position and will return to neutral position immediately when the applied force is removed from the operating plunger 17.

In operation, one operator will start a coupling on the right-hand gauge-plug 13, and when the coupling is started the operator will push on the coupling, thus pushing the shaft 3 inwardly so as to cause the bell-crank lever 19 to be rocked and thus actuate the motor controller 16 so as to start the motor 8. When the motor starts, the operator will continue to grasp the coupling until the coupling is screwed sufficiently tight on the plug to turn in the operator's hand. When the coupling turns in the operator's hand he will release the coupling and thereby permit the controller to return to neutral position and stop the motor. The operator will then pull the gauged coupling toward him so as to slide the shaft 3 outwardly relative to the housing and thereby rock the crank-lever in the reverse direction so as to actuate the motor controller in the reverse direction and cause a reverse operation of the motor to unthread the gauged coupling.

When two operators are engaged on the machine, the second operator will thread couplings on the second gauge-plug 13 while the first operator is unthreading a coupling, and the second operator will unthread couplings from the second gauge-plug while the first operator is threading couplings on the first gauge-plug.

A bracket 25 is secured on each end of the upper portion of the frame. The brackets 25 are provided with vertical slots 26 in which horizontal guide-rods 27 are adjustably mounted for vertical adjustment. A gauge-block 28 is slidably mounted on each of the rods 27. The gauge block 28 is cut away, as at 28^a, forming a shoulder 28^b adapted to engage the rear end of the gauge-plug 13.

After the coupling has been threaded on the gauge-plug 13, and while the plug is stationary prior to the motor being reversed, the operator will move the gauge-block 28 up

against the rear end of the coupling and if the coupling has been correctly threaded the shoulder 28^b of the block 28 will engage the rear end of the plug 13. Suitable tolerances 5 are allowed and the operator will know by the position of the block 28 relative to the coupling and the rear end of the gauge-plug whether the coupling threads are within these tolerances so as to gauge whether the coupling 10 has threaded sufficiently onto the plug.

While I have shown and described one specific embodiment of my invention, it will be understood that I do not wish to be limited thereto since various modifications may be 15 made without departing from the scope thereof as defined in the appended claims.

I claim—

1. A coupling gauging machine for gauging screw-threaded couplings, comprising a 20 housing, a gauge-shaft journaled in said housing, a motor, means forming a driving connection between said motor and said shaft, said shaft being slidable relative to said housing and said means, and a motor control operable by the sliding movement of said shaft 25 for starting, stopping and reversing said motor.

2. A coupling gauging machine for gauging screw-threaded couplings, comprising a 30 housing, a gauge-shaft journaled in said housing, a threaded gauge-plug on at least one end of said shaft, a motor, means including a worm-wheel connected to said shaft and a worm in mesh with said worm-wheel for 35 forming a driving connection between said motor and said shaft, said shaft being slid- 40 able relative to said housing and said worm-wheel, and a motor control operable by the sliding movement of said shaft for starting, stopping and reversing said motor.

3. A coupling gauging machine for gauging screw-threaded couplings, comprising a 45 housing, a gauge-shaft journaled in said housing and slidable relative thereto, a threaded gauge-plug on at least one end of said shaft, a worm-wheel slidably keyed to said shaft, a drive-shaft journaled in said housing, a worm on said shaft and meshed with said worm-wheel, a motor, means forming a driving 50 connection between said motor and said drive-shaft, a motor control apparatus adapted to start, stop and reverse said motor, and means

operable by sliding said gauge-shaft relative to said housing and said worm-wheel for operating said motor control.

4. A coupling gauging machine for gauging screw-threaded couplings, comprising a 55 housing, a gauge-shaft journaled in said housing and slidable relative thereto, a threaded gauge-plug on at least one end of said shaft, a worm-wheel slidably keyed to said shaft, a drive-shaft journaled in said housing, a worm on said shaft and meshed with said worm-wheel, a motor, means forming a driving connection between said motor and said drive-shaft, a motor control apparatus adapted to 60 start, stop and reverse said motor, a bell-crank lever pivotally mounted on said housing and having one end connected with said motor control apparatus and its other end engaged with said gauge-shaft, said lever being adapted to be rocked by said shaft when said shaft is slidably moved relative to said housing and said worm-wheel and said rocking movement of said lever being adapted to 65 actuate said motor control apparatus.

5. A coupling gauging machine for gauging screw-threaded couplings, comprising a 70 housing, a gauge-shaft having a circumferential groove therearound and slidably journaled in said housing so as to be capable of revolving and reciprocating relative thereto, a threaded gauge-plug secured on at least one end of said shaft, a worm-wheel slidably keyed on said shaft, a drive-shaft journaled 75 in said housing, a worm on said drive-shaft and in mesh with said worm-wheel, a motor for operating said drive-shaft, a control mechanism for starting, stopping and reversing said motor, a bell-crank lever pivotally mounted on said housing and having one arm connected with and adapted to operate said control mechanism when said bell-crank is rocked about its pivotal mounting, said bell-crank having its other arm terminating in a 80 fork which is fitted in the circumferential groove in said gauge-shaft so as to cause said bell-crank to be rocked about its pivotal mounting when said gauge-shaft is reciprocated.

In testimony whereof, I have hereunto signed my name.

RICHARD SCHOLZ.
